Primary Examiner — Bridget L Eland*Assistant Examiner* — Lauren McVey(74) *Attorney, Agent, or Firm* — Kubotera & Associates, LLC(57) **CLAIM**

The ornamental design for a stamp, as shown and described.

DESCRIPTION

FIG. 1 is a perspective view of a stamp showing my new design;
FIG. 2 is a front view thereof;

FIG. 3 is a rear view thereof;

FIG. 4 is a right side view thereof;

FIG. 5 is a left side view thereof;

FIG. 6 is a plan view thereof; and,

FIG. 7 is a bottom view thereof.

The broken lines shown in the views are included for the purpose of illustrating portions of the stamp that form no part of the claimed design.
